MACHINE FOR GRINDING LENSES

Arthur J. Holman, Brighton, and William J. Kennedy, Rochester, N. Y., assignors, by mesne assignments, to Arthur J. Holman, Rochester, N. Y.

Application March 17, 1945, Serial No. 583,244

1 Claim. (Cl. 51—73)

1 This invention relates to methods and machines for grinding lenses and, more particularly, to machines of the generating type, one object of the invention being to provide an improved method of the above character for grinding lenses with a high degree of precision and at a more rapid rate.

Another object is to provide such a method in which the lens blanks are fed toward and away from the tool by one of the generating motions, so as to facilitate the insertion and removal of the lens blanks during the continuous operation of the machine.

Another object is to produce an improved method of the character described comprising relative generating motions of the tool and work surfaces adapted to grind a wider variety of curved surfaces on the work.

A further object is to provide a simple and practical machine for carrying out the above method.

Still a further object is to provide an improved lens generating machine in a more practical and efficient type of construction capable of generating lens surfaces with increased precision and at a more rapid rate of production.

To these and other ends the invention resides in certain improvements and combinations of parts, all as will be hereinafter more fully described, the method steps and novel features being pointed out in the claims at the end of the specification.

In the drawings:

Fig. 1 is a top plan view of a lens generating machine embodying the present invention;

Fig. 2 is a side elevation of the same as viewed from the right in Fig. 1;

Fig. 3 is an enlarged sectional elevation on the line 3a—3a in Fig. 1, and

Fig. 4 is an enlarged fragmentary sectional view through the tool and lens surfaces, to illustrate the grinding action.

The present invention comprises a lens surface generating method in which a plurality of lens holding chucks are mounted in spaced relation about the periphery of a rotatable chuck holder, or wheel, which is slowly rotated within an annular grinding ring rotating at optimum grinding speed about an axis arranged, in the present embodiment of the invention, so as to intersect at right angles with the axis of rotation of the chuck holder. The grinding ring preferably comprises juxtaposed rough and fine grinding sections to which the lens blanks are fed one after another by the continuous rotation of the

2 chuck holder, so that each lens blank is subjected first to rough and then to fine grinding during a single passage over the grinding ring and each lens blank with its chuck is inserted in and removed from the chuck holder during the continuous rotation of the chuck holder. A more detailed description of the method is best understood in connection with the following description of the mechanism for carrying out the 10 method steps.

The machine at present preferred for carrying out the above method comprises a circular chuck holder 10, in the general form of a wheel having axial trunnions 11 mounted for rotation 15 in a pair of arms 12 extending in spaced relation from a forked standard 13, so as to embrace the wheel therebetween. Standard 13 is stationarily supported in any suitable manner, being shown in the present instance as carried by a base 14, 20 fixed on a supporting surface 15, forming part of a machine frame, workbench, or other suitable structure.

Chuck holder 10 has a series of chuck receiving sockets 16 formed in its periphery in radially extending, circumferentially spaced relation as shown, eight such sockets being provided in the present instance, although it will be evident that a greater or less number may be employed. The lens holding chucks, indicated generally at 17, 25 are preferably formed with cylindrical shanks 18, closely but slidably fitting in the sockets 16 which are enlarged at their outer ends for receiving and seating the chuck heads 19. The lens blanks 20 are mounted on the chucks by 30 means of the usual recessed seats, as shown, or in any other suitable manner, as well understood in the art. Each chuck shank 18 is preferably formed with a groove 21 for coaction with the end of a plunger 22, sliding in a bore 23, and pressed 35 into engagement with the chuck by a compression spring 24 between the plunger and a screw plug 25 in the outer end of the bore. The groove 21 and the plunger end are so beveled or otherwise formed that the spring actuated plunger, 40 engaging in the groove, serves to firmly and securely hold the chuck in its socket, while permitting it to be removed by a substantial outward pull, so that the chucks can be manually inserted in the sockets for grinding the lenses and removed therefrom after the lenses are ground, at 45 the outer side of the wheel, during the continuous feeding rotation thereof. Means are provided for rotating the chuck holder or wheel as hereafter described.

50 The generating tool preferably comprises an

annular ring, indicated generally at 26, Figs. 3 and 4, mounted on the circular edge or rim of a frame 27, which is of hemispherical or shell shape in the present instance and is mounted for rotation about the axis perpendicular to the plane of said edge or rim at its center. The grinding ring preferably comprises a roughing diamond grinding section 28 and a fine milling diamond section 29, the inner periphery of the latter being of cylindrical form and of the same diameter as the cylindrical bore of the section 28, as best shown in Fig. 4, to first rough grind and then fine grind the lens blank. The grinding sections 28 and 29 are preferably secured to the rim of the frame 27, by means of a circular plate 30 and a series of bolts 31 passing through openings in the plate and the grinding sections and threaded into the rim of the frame 27, as shown. The particular construction of this two-section grinding ring forms no part of the present invention, being described and claimed in the pending application for patent of Arthur J. Holman, Serial No. 589,983, filed April 24, 1945.

Frame 27 is formed in the present instance concentric with its axis of rotation with an opening 32 having an inner end portion 33 of reduced diameter. A journal 34 is fixed in the opening with a shoulder 35 seated against the reduced portion 33 of the opening, the journal having on its inner end a nut 36 binding against the inner surface of the frame for fixedly securing the journal therein. The outer end of the journal 34 is rotatably supported in bearings in spaced arms 37 at the upper end of a forked standard 38 stationarily mounted in any suitable manner, as on the frame or support 15 for the chuck holder. A boss 39 on the frame 27 and a nut 40 on the outer end of the journal 34 engage the opposite faces of the bearing arms 37 and secure the frame against endwise play in the bearings.

Frame 27 and its annular grinding ring 28 are rotated at suitable grinding speed by means of a grooved pulley 41 fixed on journal 34 between the bearing arms 37 and driven by a belt 42. The chuck holder or wheel 10 is rotated at a suitable speed for feeding the lenses to the grinding ring, by means of a reduction speed drive preferably comprising a worm gear 43, Fig. 2, fixed on an extended end 44 of one of the trunnions 11 and driven by a worm 45, fixed on a shaft 45a driven from any suitable source of power.

The axes of rotation of the chuck holder and grinding ring, in the present embodiment for grinding convex spherical surfaces, are preferably arranged to intersect each other at right angles, the chuck holder being preferably so positioned within the grinding ring that the axis of rotation of the grinding ring lies substantially in the plane of the axes of the lens chucks, and the axis of rotation of the chuck holder lies substantially in the plane of that face of the grinding ring which is in contact with the rim of frame 27 as shown in Fig. 3, but it will be obvious to those skilled in the art that such relations may be departed from for the purpose of grinding toric or other non-spherical surfaces. Thus by varying the diameter of a chuck holder relative to its grinding ring and offsetting the axis of rotation of the chuck holder from the axis of rotation of the grinding ring or by positioning said axis at different distances from the plane of the face whereon the grinding ring is mounted on frame 27 various toric surfaces may be ground.

The method steps are evident from the opera-

tion of the machine as described above in connection with its construction. Chuck holders and grinding rings may be employed in the machine having varying diameters selected to correspond with the particular lens surfaces to be ground. For grinding convex spherical surfaces, the parts are positioned in the described relation with the axes of rotation of the chuck holder and grinding ring intersecting at right angles and the axis of rotation of the chuck holder lying substantially in the plane of the inner face of the ring. With grinding ring and chuck holder rotating continuously at suitable grinding and work feeding speeds, respectively, the chucks carrying the lens blanks are inserted one by one in the sockets 16 of the chuck holder at the exposed portion of the chuck holder or wheel as each socket moves slowly toward the grinding ring. As each lens blank passes through the grinding ring, the ring sections first rough grind and then fine grind the surface to the spherical shape generated by the combined rotary motions of the grinding ring and chuck holder. After emerging from the grinding ring, each ground lens blank with its chuck is removed from the chuck holder by the operator and is replaced by a chuck carrying another lens blank to be ground.

The chuck holder is so constructed that the chucks and the lenses mounted therein may be accurately positioned for the grinding operation, while the abrading surfaces of the grinding ring may be readily trued up from time to time as required, and the construction generally is of such a nature as to be readily manufactured and maintained in condition for precise grinding work. The multiple arrangement of the chucks on the chuck holder and its rotary feeding movement into and out of the diamond milling ring facilitate the loading and unloading of the chucks and their lenses without interruption of the grinding operation, so that rapid continuous production is maintained. By the employment of chuck holders and milling rings of various diameters, as well as by variations in the relation of the axes of rotation of the elements, the method and machine may be adapted for grinding a variety of curved surfaces.

It will thus be seen that the invention accomplishes its objects and while it has been herein disclosed by reference to preferred details of method steps and structural parts, it is to be understood that such disclosure is intended in an illustrative, rather than a limiting sense, as it is contemplated that various modifications in the method steps and in the construction and arrangement of the machine parts will readily occur to those skilled in the art, within the spirit of the invention and the scope of the appended claim.

We claim:

In a lens surface generating machine, the combination of a rotatably mounted grinding ring having an internal abrading surface substantially 65 cylindrical in form, a rotatable chuck holder in the form of a wheel and having a plurality of chuck receiving sockets spaced equally around its circumference, chucks carrying lens blanks adapted to be inserted successively in said sockets 70 at a position exterior to said grinding ring, means for rotating said grinding ring about the axis of its internal abrading surface at suitable lens grinding speeds, and means for rotating simultaneously said chuck holder in spaced relation 75 to said grinding ring to effect a feeding continu-

ously, over an arcuate path, of said lens blanks toward, across and away from the internal abrading surface of said grinding ring, to grind convex spherical surfaces on said lens blanks having a radius of curvature equal to the radius of said internal abrading surface of said grinding ring and deliver said lens blanks after grinding to a position exterior to said grinding ring.
